FURNACE CONTROL APPARATUS

Donald J. Mosshart, Ardmore, Pa., assignor to
Westinghouse Electric Corporation, East Pitts-
burgh, Pa., a corporation of Pennsylvania

Application October 7, 1943, Serial No. 505,303

9 Claims. (Cl. 110—32)

This invention relates to furnace controls, more particularly to means for controlling the flow of air through the fuel bed within the furnace, and has for an object to provide improved control mechanism of this character.

Another object of the invention is to provide means, responsive to changes in the resistance of the fuel bed to flow of air therethrough, for adjusting the distribution of fuel on the fuel bed.

Yet another object of the invention is to provide means for controlling flow of air through a fuel bed by control of the fuel bed itself, as distinguished from varying the quantities of air supplied thereto by means of dampers or the like.

These and other objects are effected by the invention as will be apparent from the following description and claims taken in connection with the accompanying drawing, forming a part of this application, in which:

Fig. 1 is a horizontal sectional view through a furnace embodying the present invention;

Fig. 2 is a transverse sectional view of the furnace shown in Fig. 1, illustrating schematically control means constructed in accordance with the invention; and,

Fig. 3 is an enlarged fragmentary detail view of a modified construction.

Referring now to the drawing more in detail, the numeral 10 indicates, in its entirety, a furnace comprising front and rear walls 11 and 12, respectively, and side walls 13, the furnace having a plurality of grate bars 14 of the inverted, obtuse V-type disposed therein to provide a fuel supporting surface extending substantially from wall to wall.

A rotary impeller 15 throws or sprinkles fuel from the hopper 16, through an opening 17 in the furnace front wall 11, onto the central portion of the grate surface, in a path extending from the furnace front wall 11 to the rear wall 12, but spaced from the side walls 13, as best illustrated in Fig. 1.

A pair of masonry walls 19, surmounted by structural members in the form of I-beams 20, extend from front to rear of the furnace and support the terminal portions of the grate bars 14. The wall members 19 and 20 serve to enclose the space beneath the grate bars. A horizontal partition 21 cooperates with a pair of intermediate partitions 22, in the form of I-beams, to divide the space beneath the grate bars into a central plenum chamber A and side plenum chambers B. It will be noted that the intermediate I-beam partitions 22 provide supports for

the grate bars intermediate their terminal portions.

Primary air is supplied to the plenum chambers A and B by suitable means, such as the blower 24, the volume of air being controlled by dampers 25 and the air being admitted to the plenum chambers through the fixed orifices 26 and 27, formed in the horizontal partition 21. In order that equal pressures may be obtained in the two side plenum chambers B, there is provided a pressure balancing duct 28, providing communication between the plenum chambers.

The fuel deposited upon the central portion of the grate bars 14, by the rotary impeller 15, is limited substantially to the area of these bars overlying the central plenum chamber A, and the fuel so deposited thereon is fed laterally over the end portions of the grate bars overlying the plenum chambers B, to the dump plates 29, by transverse reciprocation of alternate grate bars. Such reciprocation of alternate grate bars is provided for by the following described mechanism: A suitable engine, such as the fluid motor 31, imparts reciprocatory motion to the rod 32, connected at its free end to the lower end of the double-ended arm 33, mounted for free rotation upon the shaft 34, which extends from front to rear of the furnace. The upper end of the arm 33 carries a pivotally-mounted dog or pawl 35 adapted to engage the teeth 36, formed about the periphery of the disc 37, which is fixedly secured to the shaft 34.

A crankarm 38 is likewise fixedly secured to the shaft 34 and is connected by link 39 to the rocker arm 40 of the shaft 41. The latter is provided with an upstanding rib 42 extending throughout its length and adapted to have its free edge received between the bifurcations of the lugs 43, which depend from the alternate reciprocable grate bars 14. It will be obvious that this mechanism provides for transverse reciprocation of the alternate grate bars, the remaining grate bars being stationary upon their supporting structure, this reciprocation of alternate bars providing for progressive feed of the fuel from the portions of the grate bars overlying the central plenum chamber A, over the end surfaces of the grate bars overlying the plenum chambers B, to the dump plates 29, from which the ash and refuse may be periodically dumped in the usual manner.

In order to control the rate of the progressive feed of fuel from the central to the side portions 55 of the grate surface, to maintain a fuel bed of

desired relative thickness, there is provided the control mechanism now to be described.

A pair of diaphragm chambers 46 and 47 are in communication with the interiors of the plenum chambers A and B, respectively, through the conduits 48 and 49, respectively. Depending rods 50 and 51 connect the diaphragms 46 and 47, respectively, with opposite ends of the bar 52, pivoted at 53 intermediate its ends on the fixed support 54. The bar 52 is provided with a plurality of pivot openings 55 in order that the location of the pivot point of the bar may be adjusted to obtain the desired action thereof. One end of the bar 52 is provided with a depending rod 56, pivotally connected to an arm 57 of a bellcrank, pivotally mounted, at 58, on a fixed support 59. The other arm 60 of the bellcrank carries a mercury switch 61 for opening and closing the electrical circuit 62, this circuit controlling action of the solenoid 63, which is connected by the spring 64 to the pawl 35 of the grate bar reciprocating mechanism. Closing of the circuit 62 will operate the solenoid 63, to tension the spring 64, thereby applying a force tending to withdraw, or disengage, the pawl 35 from the toothed disc 37. However, the spring 64 permits the pawl to remain in engagement with the teeth until the driving movement of the arm 33 has been completed. As soon as the arm 33 starts its return movement, the engaging pressure between the pawl and the teeth 36 will be relieved and the spring will withdraw the pawl from its engagement with the teeth.

In operation, it is desired that the flow of air through the layer of fuel over central plenum chamber A bears some predetermined fixed relation to the flow of air through the layer of fuel over side plenum chambers B. Since chambers A and B receive air through orifices from a common pressure P_1 , the pressures P_2 and P_3 in chambers A and B, respectively are a function of the rates of flow through these chambers to the fire. Therefore, the ratio of pressure P_2 to pressure P_3 is a measure of the relation between the rates of flow to the two portions of the fire.

If the layer of fuel over the central plenum chamber A becomes so thin, or the layer of fuel over side plenum chambers B becomes so thick that the flow of air through chamber A is greater than desired in relation to the flow through chambers B, the pressure P_2 in chamber A will drop below the desired value in relation to pressure P_3 in chambers B. This change in the pressure differential will affect the diaphragms 46 and 47 to cause downward movement of that end of the bar 52 carrying the depending rod 56, with the result that the bellcrank is moved to a position where the mercury switch 61 closes the circuit 62, thereby energizing the solenoid 63 to disengage the pawl 35 from the toothed disc 37, thus interrupting the reciprocation of the grate bars 14. Thereupon, fuel bed deposited upon the central portion of the grate surface will increase in thickness inasmuch as no fuel is being moved therefrom to the side portions, and, at the same time, the fuel remaining on the side portions will be reduced in thickness by combustion so that the original desired relation of air pressure between the plenum chambers A and B will be quickly reestablished. As soon as the pressure differential has changed to the opposite direction, the diaphragms will react to break the circuit 62, deenergizing the solenoid 63 and re-establishing the drive to reciprocate the grate bars, whereupon the fuel will again be progressively fed from the

central to the side portions of the grate surface.

Considered from another angle, the fuel bed over each of the chambers A and B may be regarded as constituting variable orifices through which air is discharged from the chambers. For any given setting of the dampers 25, the pressure P_1 below the horizontal partition 24 is constant and so is the pressure P_4 in the combustion chamber above the grates 14. The pressures P_2 and P_3 within the chambers A and B vary with changes in the resistance of the fuel bed to flow of air therethrough. Thus, the fuel bed functions as a variable discharge orifice for the chambers therebelow.

Flow through the first and the second (fuel bed) orifices are functions of the pressure drops, and as long as the orifices do not change, P_2 and P_3 remain constant. However, if the second orifice (fuel bed) changes, the pressures P_2 and P_3 required to maintain the flow change, the pressures P_2 and P_3 increasing with reduction in the second orifice area and vice versa. Increase in the second orifice area means that, for the same flow, P_2 and P_3 can be lower; but if P_2 and P_3 are lower, the pressure drop from P_1 to P_2 and P_3 is increased, causing greater flow through the first orifice.

In Fig. 3, there is illustrated a modification of the previously described control means, wherein in the drive between the pawl and toothed disc may be merely reduced, instead of completely interrupted, upon the occurrence of a change in the pressure relationship of the two plenum chambers.

In this modification the bellcrank arm 60, instead of operating a mercury switch to control an electric circuit, is directly connected to a blocking bar 70, whose free end is adapted to overlie a plurality of the teeth 36 on the disc 37, to control the number of such teeth engaged by the pawl 35 during each complete movement of the arm 33. Thus, upon occurrence of a slight change in the pressure differential between the plenum chambers A and B, the bellcrank arm 60 will move the bar 70 sufficiently to cover only a few of the teeth normally engaged by the pawl during one movement thereof. However, should a larger change in the pressure differential occur, the bar 70 would be moved farther to the right, in Fig. 3, to cover a larger number of the teeth, with the result that the pawl 35 during its return movement would slide over the bar and be prevented from engaging the teeth covered thereby. Under extreme conditions of pressure change, the bar 70 would prevent engagement of the pawl with any of the teeth 36, thereby completely interrupting operation of the bar reciprocating mechanism.

While the invention has been shown in several forms, it will be obvious to those skilled in the art that it is not so limited, but is susceptible of various other changes and modifications without departing from the spirit thereof, and it is desired, therefore, that only such limitations shall be placed thereupon as are specifically set forth in the appended claims.

What is claimed is:

1. In a stoker, means providing a fuel-supporting surface, means for depositing fuel on one portion of said surface, means for progressively feeding the deposited fuel from said one portion of the fuel-supporting surface to another portion thereof, and means for interrupting and initiating said progressive feed in response to changes

in the relative resistances of the beds of fuel on said portions to flow of air therethrough.

2. In a stoker, means providing a fuel-supporting surface, means for feeding fuel to a first portion of said surface, means for progressively feeding said fuel from said first portion to a second portion of the fuel-supporting surface, and means for decreasing the rate of said progressive feeding in response to decrease in the resistance of the fuel on the first portion of the fuel-supporting surface to flow of air therethrough.

3. In a stoker, means providing a fuel-supporting surface, means for feeding fuel to a first portion of said surface, means for progressively feeding said fuel from said first portion to a second portion of the fuel-supporting surface, and means for increasing the rate of said progressive feeding in response to decrease in the resistance of the fuel on the second portion of the fuel-supporting surface to flow of air therethrough.

4. In a stoker, means providing a fuel-supporting surface, means for feeding fuel to a first portion of said surface, means for progressively feeding said fuel from said first portion to a second portion of the fuel-supporting surface, and means for varying the rate of said progressive feeding in response to variations in the relative resistances of the beds of fuel on the first and second portions to flow of air therethrough.

5. Apparatus of the character described, comprising means providing a fuel-supporting surface, means cooperating with said first-mentioned means to provide below the latter a pair of chambers, means for feeding fuel to a first portion of the fuel-supporting surface overlying one of said chambers, means for progressively feeding fuel from said first portion to a second portion of the fuel-supporting surface overlying the other of said pair of chambers, means for admitting constant ratios of volumes of air to each of said chambers for discharge through the bed of fuel thereabove, and means for varying the rate of the progressive feed of fuel from the first to the second portion of the fuel-supporting surface in response to variations in the pressure differential between the interiors of the pair of chambers.

6. Apparatus of the character described, comprising means providing a fuel-supporting surface, means cooperating with said first-mentioned means to provide below the latter a pair of chambers, means for feeding fuel to that portion of the fuel-supporting surface which overlies one of the chambers, means for progressively feeding said fuel from said portion of the fuel-supporting surface to the portion overlying the other of said chambers, means for supplying air to said chambers under constant pressure for discharge through the fuel thereabove; and means respon-

sive to changes in the difference in pressure within the two chambers, which changes result from variations in the resistance of the fuel thereabove to flow of air therethrough, for varying the rate of progressive feed of fuel from the one to the other portion of the fuel-supporting surface.

7. Apparatus of the character described, comprising a plurality of grate members providing a fuel-supporting surface; means providing a pair of chambers beneath said grate members; means for feeding fuel to a first portion of the fuel-supporting surface overlying one of said chambers; means for progressively feeding said fuel from said first portion of the fuel-supporting surface to a second portion thereof overlying the other of said chambers; means for supplying metered air at superatmospheric pressure to the chambers for flow therefrom through the fuel thereabove; and means responsive to variations in the pressure differential between the two chambers, which variations result from changes in the resistance of the fuel thereabove to flow of air therethrough, for controlling the progressive feed of fuel from the first to the second portion of the fuel-supporting surface.

8. Apparatus of the character described, comprising a plurality of grate members providing a fuel-supporting surface; side and bottom wall structure supporting said grate members and cooperating therewith to define an enclosure therebelow; partition structure dividing the space within said enclosure into two or more chambers; means for feeding fuel to a first portion of the fuel-supporting surface overlying a first one of said chambers; means for imparting motion to a plurality of the grate members to progressively feed the fuel from said first portion of the fuel-supporting surface to a second portion thereof overlying a second one of the chambers; means for admitting a constant supply of air to each of the chambers; and means responsive to changes in the pressure differential between said first and second chambers for controlling the means for imparting motion to the grate members.

45 9. Apparatus of the character described comprising means providing a fuel-supporting surface, means cooperating with said first-mentioned means to provide below the latter a chamber, means for feeding fuel to the fuel-supporting surface to form thereon a fuel bed overlying said chamber and providing a variable discharge orifice therefrom, means providing an inlet orifice to the chamber, means for supplying air to said chamber through the inlet orifice at constant pressure, and means responsive to change in pressure within the chamber for varying thickness of the fuel bed above said chamber.
